FIREPLACE

Leonard J. Rich, Sonoma, and Clayton L. McFagan,
El Verano, Calif.

Application June 21, 1956, Serial No. 41,994

Term of patent 14 years

(Cl. D81—7)

FIG. 1

FIG. 2

FIG. 3

Figure 1 is a front elevational view of a fireplace showing our new design;

Figure 2 is a side elevational view thereof; and

Figure 3 is a cross sectional view thereof taken along the line 3—3 of Figure 1 showing the contour thereof.

We claim:

The ornamental design for a fireplace, substantially as shown.
